UNITED STATES PATENT OFFICE

DAVIS MARINSKY, OF NEW YORK, N. Y.

MULTIPLE-LINK RESILIENT BODY

Application filed March 31, 1928. Serial No. 266,157.

This invention relates to multiple link bodies of various kinds and classes and particularly to bodies of this class involving resilient elements normally maintaining the links in adjacent relation and permitting the separation and expansion thereof under tension; and the object of the invention is to provide a device of the class specified comprising oppositely disposed and alternately arranged 5 pivot portions for coupling the separate links of a body together, permitting of the separation of said links in fan-like fashion at either or both side edges of the body; a further object being to provide a device of the class 10 specified involving an insert or coupling body interposed in the structure of a belt to provide resilient expansion and contraction of the belt to compensate for the several body movements to which the belt is subjected 15 20 25 30 35 40 45 50 55 60 65 70 75 80 85 90 95 100

The invention is fully disclosed in the following specification, of which the accompanying drawing forms a part, in which the separate parts of my improvement are designated by suitable reference characters in each of the views, and in which:

Fig. 1 is a side view of the buckle portion of a belt showing one form of my improved device with part of the belt structure broken away and in section.

Fig. 2 is a partial section on the line 2—2 of Fig. 1.

Fig. 3 is a face view of a modified form 45 50 55 60 65 70 75 80 85 90 95 100

Fig. 4 is a view similar to Fig. 3 showing another modification; and,

Fig. 5 is a segmental portion of a multiple resilient link structure.

For the purpose of illustrating one general use of my invention, I have shown in Figs. 1 to 4 inclusive, three forms of devices constituting part of a belt buckle structure, whereas in Fig. 5 I have shown a segmental portion of a body which may constitute a belt or band constructed of a multiplicity of resiliently coupled links.

In Figs. 1 and 2 of the drawing, I have shown at 10 a buckle of the clamp type including a clamp bar or like member 11 arranged within the channel 10^a of the buckle and through which the free end 12 of the belt is adapted to pass and to be secured in different positions of adjustment by the clamp 11. The clamp 11 extends at one side of the buckle and is provided with a loop or ring portion 11^a, with which in the usual type of belt structure the other end 12^a of the belt is coupled, the latter being looped around the ring 11^a and secured by snap fastener or other devices 13. In carrying my invention into effect, I detach the end 12^a of the belt from the ring 11^a and mount one of my improved resilient bodies 14 within and between the belt end 12^a and the ring 11^a.

The member 14 comprises two comparatively wide end links 15 and 16, the link 15 being looped around the ring 11^a to rotatably couple the same therewith, whereas the link 16 is provided with an aperture 16^a forming a ring thereof to receive the loop end 12^a of the belt in the manner seen clearly in Fig. 2 of the drawing. Interposed between the links 15 and 16 is a narrower link 17. The side edges of the link 17 are provided with cylindrical bearings 17^a and the adjacent ends of the links 15 and 16 are provided with cylindrical bearings 15^a and 16^b. These bearings are adapted to receive the ends of two coil springs 18 and 19 arranged around pivots 20 and 21 which couple the links 15 and 17, and 17 and 16 together, and the ends of said coil springs are crossed so as to normally maintain the cylindrical bearings 15^a—17^a and 16^b—17^a normally in abutting relation, and permitting

of the separation thereof in the manner seen in Fig. 1 of the drawing, under the increased tension of said springs, it being understood that the multiple link structure, by virtue of 5 the arrangement of the pivots, permits of the expansion of both side edges of the belt structure in fan-like fashion.

The pivots 20 and 21 include cap portions 20^a and 21^a which encircle the major portion 10 of the springs 18 and 19, the walls of said caps being cut away to permit of a limited separation of the projecting ends of the springs 18 and 19. This structure is shown in the cap 20^a of Fig. 1 of the drawing. It will be understood 15 that in the relative movement of the links 15, 16 and 17, the ends of the springs 18 and 19 slidably engage the bearings 15^a, 16^b and 17^a.

The structure of the body 14 in so far as 20 the coupling of the links 15, 16 and 17 is concerned in the belt structure shown in Figs. 3 and 4 of the drawing is identical with that shown in Figs. 1 and 2. Therefore, like references will designate like parts in all of said 25 figures. In Fig. 3 of the drawing, the link 15 is modified to a slight extent by providing a slightly longer link, the ends of which are forked and fashioned to form two cylindrical bearings 15^b which encircle the central cross 30 bar 22 of a different but conventional form of buckle 23 in the form of a substantially rectangular ring, on the cross bar of which is pivotally supporting the finger 24 which passes through one of a number of apertures 35 in the free end of the belt in the usual manner. In this construction, the link 16 is similar to the link shown in Fig. 1 and includes an aperture 16^a to receive the loop end 12^a of the belt.

40 In Fig. 4 of the drawing, the structure is identical to that shown in Fig. 3 except that the link 15 is made shorter and the forked and curled end 15^b thereof encircles one end 25 of a substantially rectangular ring buckle 26 45 having a finger 27, rotatably mounted on the end 25 of said buckle. Aside from the foregoing, the structure shown in Fig. 4 is identical with that shown in Fig. 3 as well as Fig. 1 of the drawing.

50 In Fig. 5, I have shown a link body 28 which is composed of two sets of similar link members 29 and 30, two of each of said links being shown. The links 29 have side tubular bearings 29^a and the links 30 have corresponding side bearings 30^a to receive the end 55 portions of springs mounted on the pivotal ends 31 employed for coupling the adjacent and alternate ends of said links. These springs are of the same structure as disclosed 60 in Figs. 1 and 2 of the drawing, and normally serve to maintain the adjacent sides of the links 29 and 30 in abutting relation under tension and permit of the separation of said links at either side of the body in fan-like 65 fashion under the increased tension of said

springs, it being noted that one end of each spring extends into a cylindrical bearing 29^a of a link 29, and the other end of such spring into an adjacent bearing 30^a of a link 30. The enclosing and stop movement caps 32 70 similar in all respects to the caps 20^a and 21^a, Fig. 1, are employed on the pivots 31 of the links 29 and 30. The structure shown in Fig. 5 may be used in the manufacture of 75 expandible and contractable articles of any kind or class, and not necessarily an insert as disclosed in Figs. 1 to 4 inclusive, for example, in the construction of a belt, bracelet, strap or the like.

It will also be understood that my invention is not necessarily limited to the use of three links and two pivotal connections therefor as seen in Figs. 1 to 4 inclusive, nor am I necessarily limited to any particular manner of coupling the same with a belt structure or the buckle of a belt. As a matter of fact, the body 14 may constitute an integral part of the belt structure and various other changes in and modifications of the construction herein shown and described may be made within the scope of the appended claims 85 without departing from the spirit of my invention or sacrificing its advantages.

It will be noted that in the forms of construction shown in Figs. 1 to 4 inclusive, that the free end portion of the belt after it has been passed through and engaged by the buckle, overlies and covers the member 14 so that the same becomes substantially invisible or concealed. This may be noted upon a consideration of Figs. 1 and 2 of the drawing, the overlapped portion of the belt being broken away in Fig. 1, but is shown in section in Fig. 2.

Having fully described my invention, what I claim as new and desire to secure by Letters Patent, is:

1. A body of the class described comprising a plurality of links having pivotal connections disposed alternately at opposite side edges of said body, and tensional means at the pivot portions of said links and engaging adjacent links for normally maintaining the same, under tension, in abutting relation and permitting the separation thereof under the increased tension of said means.

2. A body of the class described comprising a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, and means for movably supporting said end portions in connection with adjacent links.

3. A body of the class described compris-

ing a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, means for movably supporting said end portions in connection with adjacent links, and means encircling said springs and cooperating with the projecting end portions thereof for limiting the separation of said links.

4. A body of the class described comprising a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, means for movably supporting said end portions in connection with adjacent links, means encircling said spring and cooperating with the projecting end portions thereof for limiting the separation of said links, and means whereby a strap member may be coupled with a link at one end of said body.

5. A body of the class described comprising a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, means for movably supporting said end portions in connection with adjacent links, means encircling said springs and cooperating with the projecting end portions thereof for limiting the separation of said links, means whereby a strap member may be coupled with a link at one end of said body, and a buckle on a link at the other end of said body.

6. A body of the class described comprising a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, means for movably supporting said end portion in connection with adjacent links, means encircling said

springs and cooperating with the projecting end portions thereof for limiting the separation of said links, and the link at one end of said body involving a buckle structure.

7. A body of the class described comprising a plurality of links having pivotal connections disposed alternately at opposite side edges of said body, tensional means at the pivot portions of said links and engaging adjacent links for normally maintaining the same, under tension, in abutting relation and permitting the separation thereof under the increased tension of said means, said tensional means involving coil springs having projecting end portions, means for movably supporting said end portions in connection with adjacent links, means encircling said springs and cooperating with the projecting end portions thereof for limiting the separation of said links, and the link at one end of said body involving a buckle structure pivotally supported in connection with said link.

8. The combination with a buckle of a multiple link body, the links of said body being pivotally coupled by pivots the axis of which are perpendicular to the longitudinal and horizontal plane of said links, coil springs on the pivots of said links and having projecting end portions engaging the adjacent links and normally maintaining adjacent edges of said links in abutting relation under the tension of said spring.

9. The combination with a buckle of a multiple link body, the links of said body being pivotally coupled, coil springs on the pivotal connections of said links and having projecting end portions engaging adjacent links and normally maintaining said links in abutting relation under the tension of said spring, and the pivotal connection of said links being disposed at opposite sides of said body permitting the separation of said links at opposite sides of said body in fan-like fashion.

10. The combination with a buckle of a multiple link body, the links of said body being pivotally coupled, coil springs on the pivotal connections of said links and having projecting end portions engaging adjacent links and normally maintaining said links in abutting relation under the tension of said spring, the pivotal connection of said links being disposed at opposite sides of said body permitting the separation of said links at opposite sides of said body in fan-like fashion, and means on the pivotal connection of said links cooperating therewith to limit the expansion thereof.

11. The combination with a buckle of a multiple link body, the links of said body being pivotally coupled, coil springs on the pivotal connections of said links and having projecting end portions engaging adjacent links and normally maintaining said links in abutting relation under the tension of said

- spring, the pivotal connection of said links being disposed at opposite sides of said body permitting the separation of said links at opposite sides of said body in fan-like fashion, means on the pivotal connection of said links cooperating therewith to limit the expansion thereof, and means for detachably coupling one end of a belt with one of the links of said body.
12. A buckle adapted to be mounted on one end of a belt or strap comprising a part with which the strap or belt is coupled and a part for engagement with the free end of said strap or belt, and means interposed between said parts for tensionally maintaining said parts normally in adjacent relation and permitting the separation thereof under tension.
13. A buckle adapted to be mounted on one end of a belt or strap comprising a part with which the strap or belt is coupled and a part for engagement with the free end of the strap or belt, and means interposed between said parts for tensionally maintaining said parts normally in adjacent relation and permitting the separation thereof under tension, said means comprising a link pivoted at opposite side portions of the first named parts and interposed therebetween permitting the separation of said parts at opposite sides thereof in fan-like fashion.
14. A body of the class described involving a plurality of spring loops disposed at opposite side edges of said body, said loops having radially extending portions directly inwardly with respect to said side edges, and means for coupling the radially extending portion of a loop at one side of said body with the radially extending portion of the adjacent loop at the opposite side of said body to form a continuous resilient member of said body.
15. A body of the class described involving a plurality of spring loops disposed at opposite side edges of said body, said loops having radially extending portions directed inwardly with respect to said side edges, means for coupling the radially extending portion of a loop at one side of said body with the radially extending portion of the adjacent loop at the opposite side of said body to form a continuous resilient member of said body, and the arrangement of said radially extending portions with respect to said spring loops being such as to increase the tension of said loops in the operation of separating the same in extending said body.

In testimony that I claim the foregoing as my invention I have signed my name this 30th day of March, 1928.

DAVIS MARINSKY.
